UNITED STATES PATENT OFFICE.

FRANKLIN G. NEUBERT, OF WATERBURY, CONNECTICUT, ASSIGNOR TO
THE SCOVILL MANUFACTURING COMPANY, OF SAME PLACE.

DESIGN FOR A HANDLE FOR BICYCLE-BRUSHES.

SPECIFICATION forming part of Design No. 25,775, dated July 14, 1896.

Application filed November 5, 1895. Serial No. 568,060. Term of patent 7 years.

To all whom it may concern:

Be it known that I, FRANKLIN G. NEUBERT, of Waterbury, in the county of New Haven and State of Connecticut, have invented a new 5 Design for the Handles of Bicycle-Brushes; and I do hereby declare the following, when taken in connection with the accompanying drawing, and the letters of reference marked thereon, to be a full, clear, and exact description of the same, and which said drawing constitutes part of this specification and represents a perspective view of a bicycle-brush having a handle embodying my design.

This invention relates to a design for handles for bicycle-brushes, and the design consists in the configuration shown in the accompanying illustration.

The hollow cylindrical handle A is of uniform diameter throughout its length. Near 20 its inner end it is formed with a long, narrow slot A', the body of which is in line with its

longitudinal axis. The inner end a of the slot is turned outward, while the outer end a' of the slot is turned in the opposite direction and inward, the slot in its entirety resembling 25 one of the f-holes of a violin. The outer end of the body A is finished by a knurled cap A². The open inner end of the body is encircled by a roughened band B, carrying a screw which enters the slot and is connected 30 with the brush C.

I claim—

The design for a handle for a bicycle-brush, as herein described and shown in the accompanying illustration.

In testimony whereof I have signed this specification in the presence of two subscribing witnesses.

FRANKLIN G. NEUBERT.
